UNITED STATES PATENT OFFICE.

J PAUL CLARKSON, OF ST. CHARLES, MINNESOTA.

MILK-CAN BRUSH.

No. 922,456.

Specification of Letters Patent.

Patented May 25, 1909.

Application filed December 14, 1908. Serial No. 467,450.

To all whom it may concern:

Be it known that I, J PAUL CLARKSON, of St. Charles, Winona county, Minnesota, have invented certain new and useful Improvements in Milk-Can Brushes, of which the following is a specification.

The object of my invention is to provide a brush of simple economical construction that is capable of being collapsed for insertion into the can and expanded or unfolded after such insertion, to bring its bristles in position to contact with the walls of the can.

A further object is to provide a can washer, which will always retain its proper form having no tendency to warp or check after being wet.

A further object is to provide a washing device, which will adapt itself to the irregularities of the inner surface of the can.

20 The invention consists generally in various constructions and combinations, all as hereinafter described and particularly pointed out in the claims.

In the accompanying drawings, forming 25 part of this specification, Figure 1 illustrates the folded position of the washing device ready to be inserted into the can. Fig. 2 is a similar view, showing the device unfolded. Fig. 3 is a sectional view on the line X—X of Fig. 2. Fig. 4 is a view of a modified construction, showing the device adapted for use in fruit jars or small cans.

In the drawings, 2 and 3 represent frames, 35 preferably of wire of suitable gage, having loops 4 formed therein. On the lower end and the outer rails of these frames, sheet metal holders 5 are provided having flanges 6, between which the bristles 7 are secured. These bristles are of suitable length to contact with the walls of the can and thoroughly clean the same. The outer rails of the frames 2 and 3 have loops 8 formed therein, whereon heads 9 of handles 10 and 11 are swiveled. These handles extend through the loops 4 and one of them has an off-set portion 12, 45 around which the other handle 10 is coiled in a series of loops 13. The off-set portion 12 serves as an axis, on which the loops 13 revolve to open or close the cleaning device. 50 A loop 14 is formed in the upper end of the handle 11 and serves as a crank for operating

the handle 11 in folding or unfolding the brushes. A loop 15 is formed on the handle 10, to be grasped in one hand, as the loop 14 is operated back and forth with the other 55 hand.

In Fig. 4 I have illustrated a modified construction, which consists in mounting the sheet-metal, bristle-holding plates 16 directly on the handles 17 and 18, instead of 60 providing an intermediate spring frame, as in the construction shown in Fig. 2. This frame is adapted particularly for cleaning the inside surfaces of fruit jars or cans. In the use of the device, the brushes are folded 65 against one another, as indicated in Fig. 1, to allow the article to be thrust into the throat or neck of the can. The insertion being made and the operator holding the loop 15 in one hand, will move the loop 14 half a revolution or to the position indicated in Fig. 2 and unfold or expand the brush. Both handles are then grasped with one hand and sufficient pressure applied to force the bristles at the bottom against the bottom of the can 70 and upon revolving the brush, the inside of the can will be thoroughly cleaned.

This type of brush may, with suitable variation in shape, be readily adapted for cleaning receptacles of various kinds, such as 80 tubes and bottles, as well as cans. I do not wish to be confined therefore, to the application of the invention, as illustrated herein.

I claim as my invention:

1. A can-washing brush, comprising frames 85 of spring material having inner and outer rails, said inner rails having loops therein and bristles mounted on said outer rails, and handles having swiveled connections at one end with said outer rails and passing through 90 said loops, one of said handles being mounted on the other one so as to be capable of rotary movement thereon.

2. A device of the class described, comprising frames of spring wire substantially 95 triangular in form having their lower rails downwardly inclined toward the middle of the brush, and bristles mounted on the outer rails of said frames, handles pivotally connected with the outer side rails of said 100 frames and having loose connections with their inner rails, one of said handles being

mounted on the other one so as to be capable of a rotary movement thereon, and said handles being adapted, when downward pressure is applied thereto to bend said frames and force the bristles thereon against the bottom and lower corners of the article that is being cleaned, substantially as described.

In witness whereof, I have hereunto set my hand this 7th day of December, 1908.

J PAUL CLARKSON.
